(57) **CLAIM**

I claim the ornamental design for a cap for liquid containers, as shown and described.

DESCRIPTION

FIG. 1 is a front top perspective view of the cap for liquid containers;

FIG. 2 is a top view of the cap for liquid containers;

FIG. 3 is a bottom view of the cap for liquid containers;

FIG. 4 is a back top perspective view of the cap for liquid containers;

FIG. 5 is a right-side view of the cap for liquid containers;

FIG. 6 is a left-side view of the cap for liquid containers;

FIG. 7 is a front top perspective view of the cap for liquid containers open;

FIG. 8 is a top view of the cap for liquid containers open;

FIG. 9 is a bottom view of the cap for liquid containers open;

FIG. 10 is a back top perspective view of the cap for liquid containers open.

FIG. 11 is a right-side view of the cap for liquid containers open;

FIG. 12 is a left-side view of the cap for liquid containers open;

FIG. 13 is a top side perspective view of the cap for liquid containers open; and

FIG. 14 is a bottom side perspective view of the cap for liquid containers open.

1 Claim, 8 Drawing Sheets
